APPARATUS FOR GRINDING DUAL FLATS
ON CARDS

Robert Bain Jenkins, Sr., P.O. Box 1160, Gastonia, N.C.
Filed June 12, 1963, Ser. No. 287,389
5 Claims. (Cl. 51—243)

This invention relates to revolving flat card machines which have been converted from a single endless series of flats to a dual series of flats.

Card machines having a single endless series or set of revolving flats overlying the main card cylinder, and extending from adjacent the licker-in to a point adjacent the doffer cylinder, have been in use for many years. Recently it has been found that card machines could be 15 operated at faster speeds and would produce a web or sliver of better quality by providing two successive series or sets of revolving card flats overlying the main cylinder. Thus, since there are a large number of conventional card machines already in use, many of them are being converted to include two series of card flats instead of one.

As is well known, each card flat has an elongate, narrow, strip of card clothing thereon which includes closely spaced bent wires whose free ends are inclined rearwardly with respect to the direction of movement of the proximal wire-covered surfaces of the flats and the main cylinder. Since the flats must move parallel with, at a slower speed than, and in close proximity to the wire-covered surface of the main cylinder, the card flats must be accurately ground from time to time while on the card machine. When the grinding operation on one machine is completed, the grinding apparatus is lifted off of standards, which remain attached to the machine arches, so the grinding apparatus will not interfere with the operation of the card flats and may be used to grind the flats of other card machines.

In the conversion of card machines in the aforesaid manner, it becomes necessary to provide a separate mounting means in association with each of the two series of card flats to support the grinding apparatus including its grinding roll, the cradle therefor and the associated bearing members. Conventionally, and as shown in U.S. Patent No. 620,353, for example, such mounting means comprises a pair of stand members or standards adjustably secured to the arches at opposed sides of and rearwardly of the vertical plane of the axis of the arches of the card machine. Thus, the standards project upwardly and rearwardly at an angle in one direction and have correspondingly inclined bearing surfaces against which the bearing members rest so that shoes on the lower portions of opposed ends of the cradle, and to which the bearing members are secured, may rest against the ends of the flats moving with the upper run of the corresponding series.

It is apparent that the cradle and bearing members would gravitate away from the bearing surfaces of the standards if such standards were inclined upwardly and forwardly in the opposite direction from said one direction, as would be required to effect the grinding of a separate series of flats overlying a forward angular portion of the arches and the main cylinder. If the conventional standards were interchanged from one side of the card machine to the other, the flats would be moving in a direction away from the bearing surfaces and would then cause vibration of the bearing members toward and away from the bearing surfaces of the standards which would result in inaccurate grinding of the flats. Thus, it has been necessary heretofore to remove the front set of flats from the machine and install the same on a special grinding machine in order to grind the same.

It is therefore an object of this invention to provide an improved means for supporting a grinding apparatus

2

of the type described adjacent a forward angular portion of the card machine arches and wherein means are provided for maintaining the flat bearing surfaces of the bearing members in slidable engagement with mating bearing surfaces of grinder stand members whose mating bearing surfaces are inclined upwardly and forwardly at an angle and face forwardly toward the direction opposite from that toward which moves the corresponding upper run of the front set of card flats, and wherein very minor modifications are made in the grinding apparatus so that it may also be readily mounted on the existing conventional grinder stand members adjacent the aforementioned rear angular portion of the arches of the card machine for grinding the rear set of card flats.

It is another object of this invention to provide a grinder supporting means for use adjacent the forward angular portion of the card machine arches which may be manufactured by modifying the existing types of grinder bearing members and grinder stand members such as are conventionally used adjacent the rear angular portion of the card machine arches.

It is a more specific object of this invention to provide supporting means of the character described for each end of the grinding roll, which supporting means comprises a pair of members wherein one of the members is in the form of a bearing member attached to the corresponding end of a cradle having a shoe portion thereon adapted to rest upon and to be displaced by corresponding ends of flats moving therebeneath and wherein the bearing member has the corresponding end of the grinding roll journaled thereon. The other member is in the form of a grinder stand or support member fixed to the corresponding arch of the card machine, said members having interengaging angularly disposed bearing surfaces thereon with a guide plate removably secured to the outer surface of one of the members and having an elongate slot therein through which guide means or pins extend from the outer surface of the other of the members, and the relative positions of the bearing surfaces, the guide means, and the slot being such as to maintain the bearing surfaces in slidable engagement with each other so the bearing member may move upwardly and downwardly relative to but in precise parallel relationship to the mating bearing surface of the standard, thereby permitting the shoe on the corresponding end of the cradle to rest against and to be accurately displaced by the corresponding ends of the card flats as they move beneath the shoe during the grinding operation.

Some of the objects of the invention having been stated, 50 other objects will appear as the description proceeds, when taken in connection with the accompanying drawings, in which—

FIGURE 1 is a side elevation of a revolving flat card machine, with parts broken away, showing the same 55 equipped with two endless sets or series of card flats, with a conventionally mounted grinding apparatus being positioned adjacent the right-hand or rear set of card flats and the improved grinder supporting apparatus of the present invention being positioned adjacent the left-hand or front series of card flats;

FIGURE 2 is an enlarged fragmentary elevation of the upper left-hand portion of FIGURE 1 and showing the improved grinder supporting apparatus more in detail;

FIGURE 3 is a fragmentary sectional plan view taken 65 substantially along line 3—3 in FIGURE 2;

FIGURE 4 is an enlarged fragmentary sectional plan view taken substantially along line 4—4 in FIGURE 2;

FIGURE 5 is a fragmentary elevation, partially in section, looking at the left-hand side of the structure shown in FIGURE 2 substantially along line 5—5; and

FIGURE 6 is an enlarged substantially vertical sec-

tional view taken substantially along line 6—6 in FIGURE 2.

Referring more specifically to the drawings, the numeral 10 broadly designates one of the arches or main side frame members of a carding machine. The arch 10 is of somewhat semi-circular form and its peripheral edge conforms substantially to the shape of a card cylinder 11 which is driven to rotate in a counterclockwise direction in FIGURE 1 by means of electric motor 12. Textile fibers are directed to main card cylinder 11 from a conventional licker-in section 13 and the fibers picked up by the clothing c (FIGURE 5) on the card cylinder 11 are successively moved past the lower reaches of rear and front endless series or sets of card flats respectively broadly designated at 14, 15. The carded fibers are removed from card cylinder 11, adjacent the front portion thereof, by the usual doffer cylinder 16, as is well known.

The individual flats of each series 14, 15 are indicated at 20 and are in the form of elongate flat bars whose outer surfaces are provided with card clothing 21 in the form of closely spaced bent wires. As shown in FIGURE 5, the wire clothing 21 terminates at a point spaced inwardly from the free ends of the bars of the flats and the end portions of the bars forming the lower runs of the series 14, 15 must move in sliding engagement with an arcuate race bar or "flexible bend" 22 adjustably secured to the corresponding arch 10 for maintaining the free ends of the wires of the clothing 21 on the flats 20 in accurately spaced relation with respect to the card clothing on the main cylinder 10.

The corresponding ends of card flats 20 are pivotally connected to endless card flat chains 23 which, as shown in the upper portion of FIGURE 5, are spaced inwardly from the corresponding free end portions of the card flats 20. The chain 23 and card flats 20 of the series 14 overlie a forward angular portion of main cylinder 11 and arch 10 and are mounted on a pair of lower and upper drums or rollers 25, 26 fixed on respective shafts 27, 28. The flats 20 and chain 23 of the front series 15 overlie a forward angular portion of card cylinder 11 and arch 10 and are mounted on front and rear rollers 31, 32 mounted on respective shafts 33, 34.

Shafts 27, 28, 33, 34 are mounted in respective bearing stands 35-38 suitably secured to the outer surface of arch 10 and projecting upwardly and substantially radially therefrom. One of the shafts 28 or 33 is driven by well-known means, not shown, and transmits rotation to the other of the latter shafts by means of an endless sprocket chain 41 and sprocket wheels 42, 43 fixed on corresponding ends of the respective shafts 28, 33. Thus, both sets or series of flats 14, 15 are driven to move in the same direction and wherein the lower runs thereof move forwardly in the same direction as the main card cylinder but at a slower speed than the peripheral speed of the main card cylinder 11. Since the points of the wires of the card clothing 21 on the flats 20 of both series 14, 15 project upwardly or outwardly with respect to the upper runs of the corresponding card flat series 14, 15, a conventional flat grinding apparatus, broadly designated at 46, is shown in operative position for grinding the flats in series 14 at the rear angular portion of arch 10 and cylinder 11, and a card flat grinding apparatus embodying the present invention and broadly designated at 47 is shown in operative position with respect to the flats in series 15 at the forward angular portion of arch 10 and main cylinder 11 in FIGURE 1. The supporting means at only one end of each of the card flat grinding apparatuses 46, 47 is shown in the accompanying drawings, but it is to be understood that similar mounting means are provided at the opposite ends of the respective card flat grinding apparatuses 46, 47 at the opposite side of the machine from that shown in FIGURE 1.

As heretofore stated, the supporting means of the present invention and associated with the grinding apparatus 47 may be manufactured by modifying the existing

types of grinder bearing members and grinder stand members or standards such as are conventionally used adjacent the rear angular portion of the card machine arch 10 and which are shown in association with the conventional grinding apparatus 46. Accordingly, only the grinding apparatus 47 will be described in detail and those parts of the grinding apparatus 46 corresponding to like or similar parts of the grinding apparatus 47 shall bear the same reference characters with the prime notation added, where applicable, for purposes of comparison between the two apparatuses 46, 47 and for purposes of brevity.

Referring to FIGURES 1, 2, 4 and 5, the grinding roll 50 of apparatus 47 is mounted on a shaft 51 which may be rotated in any desired manner and is journaled in sleeve bearings B only one of which is shown. Each sleeve bearing B is carried by an adjustable bearing member or end plate 53 adjustably secured to the outer surface of a shoe 54 integral with an end frame member 55 of a cradle broadly designated at 56, it being understood that an end frame member identical to member 55 is positioned at the opposite side of the machine adjacent the opposite end of the grinding roll 50 from that shown in FIGURES 1, 2, 4 and 5. Frame member 55 is provided with a pair of upper and lower ears a, b and the ears on the two end frame members are interconnected by cross-rods c, d.

The bearing member 53 is mounted on the end frame member 55 and its shoe 54 to be adjustable upwardly and downwardly thereon in any desired manner. Accordingly, a tongue 57 (FIGURE 4) extends from the inner surface of bearing member 53 and fits in a corresponding longitudinally or substantially vertically extending groove or recess formed in the outer surface of the corresponding end frame member 55. An adjustment screw 61 loosely penetrates an ear portion 62 (FIGURE 5) projecting inwardly from the upper end of bearing member 53 and has a collar 63 thereon which engages the lower surface of ear 62. Adjustment screw is threaded into the corresponding portion of end frame member 55 so that the adjustment screw 61 may be rotated for raising or lowering the corresponding bearing member 53 relative to the end frame member 55 of cradle 56.

Bearing member 53 is locked in adjusted position against the shoe 54 of the corresponding end frame member 55 by a suitable locking screw 64 which loosely penetrates a slot 65 in bearing member 53 and is threaded into shoe 54. The lower surface or edge of the shoe 54 at each side of the carding machine is shaped in a well-known manner so as to rock the individual flats 20 during movement of the flats beneath the corresponding shoe 54. Since the shoe 54 rests upon the flats, it is apparent that the relative position between the grinding roll 50 and the shoe 54 determines the manner in which the wires of the flats 20 are ground.

The cradle end frame member 55 has a pin 67 projecting outwardly therefrom at a point rearwardly of the rear bearing surface 69 of bearing member 53 and which is adapted to be positioned in a recess e (FIGURES 2 and 3) formed in a mating bearing surface 70 on an upwardly projecting arm 71 of a grinder support member broadly designated at 72. The front end of slot e is open so that, when the grinding apparatus 47 is not in use, the bearing member 53 and end frame member 55 of cradle 56 may be moved forwardly to remove the pin 67 from slot e, whereupon the pin 67 may then be positioned on a higher level in a recess f which is also formed in the front bearing surface 70 of grinder support member 72.

The grinder support member 72 on each side of the machine is suitably secured to a corresponding bracket 75 and may be angularly adjusted relative to bracket 75 in the manner disclosed in said U.S. Patent No. 620,353. Bracket 75 is suitably secured to the outer surface of arch 10, as by means of a screw 76 which penetrates a longitudinally extending adjustment slot 77 formed in bracket 75 and is threaded into a guide block 80 fixed to the arch 10.

The upper end of bracket 75 is spaced beneath the corresponding shoe 54 and has a pair of laterally opposed arcuate guide surfaces 82, 83 thereon upon which the exposed ends of the flats 20 are adapted to move, in sliding engagement therewith, in the course of movement thereof toward and away from the grinding wheel 50 and to thus insure that boss portions 20a on the corresponding ends of the flats 20, and opposite from the wires on the flats 20, are moved into engagement with an inwardly projecting guide member 84 integral with bracket 75, the latter guide member 84 being positioned substantially radially of the axis of grinding roll 50. The guide member 84 permits the flats 20 to rock upon the same as the upper surfaces of the free end portions thereof follow the contour of the lower surface of the corresponding shoe 54, thus insuring that the flats are properly positioned during the grinding operation.

The parts heretofore described in association with the grinding apparatus 47 are conventional and, as a matter of fact, the corresponding parts associated with the conventional grinding apparatus 46 adjacent the rear angular portion of arch 10 and main cylinder 11 may be identical to those parts heretofore described with respect to the grinding apparatus 47.

It can readily be seen in the right-hand portion of FIGURE 1 that the mating surfaces 69', 70' will remain in engagement with each other throughout the grinding operation, because the bearing member 53' rests against the correspondingly upwardly and rearwardly inclined surface 70' of support member 72'. Also, the upper or outer run of the card flat series 14 moves downwardly and rearwardly toward the front or upper bearing surface 70' of support member 72' during the grinding operation and further assists in maintaining the bearing surface 69' of bearing member 53' against and in sliding engagement with the mating bearing surface 70' of grinder support 72' as the lower or inner surface of the shoe 54' rests against and is shifted inwardly and outwardly by the card flats 20 moving therebeneath.

However, since the bearing member 53 and the support member 72 associated with each end of the grinding apparatus 47 must extend in substantially the opposite angular direction from that at which the bearing surfaces 69', 70' extend in order to effect the grinding of the flats 20 of the front series 15, it is apparent that the cradle 56 and the bearing member 53 on each end thereof would gravitate away from the support member 72. Also, as heretofore stated, if the conventional support member at the opposite side of the machine from the support member 72' shown in FIGURE 1 was positioned at the same side of the machine as that shown in FIGURE 1 for supporting the grinding apparatus 47, the bearing surface corresponding to surface 70' on the support member would be facing toward the direction toward which the corresponding upper or outer run of the card flat series 15 is moved during the grinding operation.

Thus, in the latter instance, the movement of the card flats against the lower surface of the corresponding bearing member would cause the bearing member to vibrate or move away from the corresponding support and this would result in such faulty grinding of the flats that they would probably have to be discarded. Accordingly, in order that the grinding apparatuses 46, 47, including the cradles 56, 56' and bearings 53, 53' may be interchangeable and may be used for grinding the flats of other card machines, novel means are provided for maintaining the flat bearing surfaces of the bearing members, such as bearing member 53, in sliding engagement with the mating bearing surfaces of grinder stand members or support members, such as the support member 72.

To this end, each pair of members 53, 72, only one pair of which is shown in the present drawings, has a guide plate 90 positioned against the outer surfaces thereof and being secured to one of the members of said pair while the other of the members of said pair has guide means

cooperating with the plate 90 to maintain the surfaces 69, 70 in engagement with each other while permitting relative sliding movement therebetween. In this instance, guide plate 90 is removably secured to the outer surface of bearing member 53 by means of a pair of vertically spaced or longitudinally spaced shoulder screws 91 whose threaded portions are threaded into the bearing member 53 and whose shoulder portions are closely fitted in corresponding bores 92 (FIGURE 4) extending through guide plate 90.

Guide plate 90 has an elongate slot 94 therethrough which extends in precise parallel relationship to the bearing surfaces 69, 70 and through which guide elements or pins 95 loosely extend, there being two of the pins 95 shown in FIGURE 2. The pins 95 are suitably secured to and project outwardly from the outer face of the standing portion 71 of bracket 72. The relative positions of the rear wall of slot 94, the rear surfaces of pins 95 and the bearing surfaces 69, 70 of members 54, 72 are such that the pins 95 will maintain the rear bearing surface 69 of bearing member 53 in precise parallel slidable engagement with the front bearing surface 70 of support member 72, while permitting the bearing member 53 to move upwardly and downwardly as the successive flats 20 move into engagement with the specially shaped lower surface of the shoe 54.

It is thus seen that, although the fixed bearing surface 70 of the grinder stand member or support member 72 faces downwardly and forwardly and extends at an angle substantially radially with respect to the axis of the arch 10 and main cylinder 11, the bearing member 53 and, thus, the grinding roll 50 may move vertically or substantially radially with respect to the axis of main cylinder 11 while the lower specially configured surface of the shoe 54 of cradle 56 will remain accurately positioned with respect to the guide projection 84 (FIGURE 5) on the corresponding bracket 75. It is apparent that the grinding apparatus 47 may readily be removed from the grinder support member 72 and the bracket 75 for use in the grinding of the flats on another carding machine or for use in place of the grinding apparatus 46 in the right-hand portion of FIGURE 1, simply by removing the screws 91 from the corresponding bearing member 53 and plate 90 at each side of the machine.

Since the screws 91, the holes in the bearing member 53 into which the screws 91 are threaded, and the bores 92 for the shoulder portions of the screws 91, and formed in the plate 90, are accurately positioned with respect to the bearing surfaces 69, 70, the pins 95 and the rear wall of the elongate slot 94, it is apparent that the grinding apparatus 47 may readily be installed on the support member or grinder stand member 72 whenever the grinding operation is to be completed. Of course, when the grinding apparatus 47 is not being used, it may be completely removed from the machine by removing the screws 91 from plate 90 and the corresponding bearing member 53 or, once the screws 91 and plate 90 are removed from each bearing member 53, it is apparent that the entire cradle 56 and its bearing members and grinding roll 50 may be moved forwardly to remove the corresponding pins from the recesses e on each side of the machine and may then be moved upwardly so that the pins 67 may rest in the corresponding notches or recesses f to support the grinding apparatus 47 in inoperative position while it is not being used.

In the drawings and specification there has been set forth a preferred embodiment of the invention and, although specific terms are employed, they are used in a generic and descriptive sense only and not for purposes of limitation, the scope of the invention being defined in the claims.

I claim:

1. In an apparatus for grinding the flats on a revolving flat card machine, said apparatus including a cradle, a bearing member on said cradle, a grinding roll journaled

for rotation on said bearing member, a grinder support member secured to said carding machine and extending upwardly therefrom at an angle, said support member having a bearing surface extending at an angle and facing downwardly, and said bearing member having a bearing surface adapted to slidably move against the downward facing bearing surface of said support member; the combination therewith of a plate positioned against said members, bridging said bearing surfaces and secured to one of said members, said plate having an elongate slot therein spaced from but extending parallel to the bearing surfaces of said members, and guide means carried by the other of said members and penetrating said slot and being spaced from said bearing surfaces a distance substantially equal to the distance that the slot is spaced from said bearing surfaces for maintaining said bearing surfaces in slidable engagement with each other.

2. In a card-flat grinding apparatus having a bearing member, a grinding roll journaled on said bearing member, a stand member adapted to be secured in a fixed position on a card machine, and said members having mating flat bearing surfaces thereon and also having flat outer surfaces thereon; the combination therewith of a guide plate fixed to the flat outer surface of said bearing member and extending adjacent the outer surface of said stand member, means on said stand member for guiding said plate in a path parallel to said bearing surfaces, and said last-named means being operable to maintain the bearing surface of said bearing member in engagement with the bearing surface of said stand member.

3. In a card-flat grinding apparatus having a bearing member, a grinding roll journaled on said bearing member, a stand member adapted to be secured in a fixed position on a card machine, and said members having mating flat bearing surfaces thereon and also having flat outer surfaces thereon; the combination therewith of a guide plate fixed to the flat outer surface of said bearing member and extending adjacent the outer surface of said stand member, guide means carried by and extending outwardly from said stand member, and said plate having an elongate slot therethrough extending parallel with said bearing surfaces and mating with said guide means so as to permit said bearing member to move in sliding engagement with said stand member while maintaining said bearing surfaces in engagement with each other.

4. In an apparatus for grinding the flats on a revolving flat card machine, said apparatus including a cradle, a bearing member on said cradle, a grinding roll journaled

for rotation on said bearing member, a grinder support member secured to said carding machine and extending upwardly therefrom at an angle, said support member having a bearing surface extending at an angle and facing downwardly, and said bearing member having a bearing surface adapted to slidably move against the downwardly facing bearing surface of said support member; the combination therewith of a plate positioned against said members and bridging said bearing surfaces, means removably securing said plate to one of said members, said plate having an elongate slot therein spaced from but extending parallel to the bearing surfaces of said members, and a pair of guide pins projecting outwardly from the other of said members and penetrating said slot and being spaced from said bearing surfaces a distance substantially equal to the distance that the slot is spaced from said bearing surfaces for maintaining said bearing surfaces in slidable engagement with each other.

5. In an apparatus for grinding the flats on a revolving flat card machine, said apparatus including a cradle, a bearing member on said cradle, a grinding roll journaled for rotation on said bearing member, a grinder support member secured to said carding machine and extending upwardly therefrom at an angle, said support member having a bearing surface extending at an angle and facing downwardly, said bearing member having a bearing surface adapted to slidably move against the downwardly facing bearing surface of said support member and said members have flat outer surfaces thereon; the combination therewith of a plate positioned against the outer surfaces of said members, means removably securing said plate to the outer surface of said bearing member, said plate having an elongate slot therein spaced from but extending parallel to the bearing surfaces of said members and registering with said stand member, a pair of longitudinally spaced pins fixed to and projecting outwardly from said stand members and penetrating said slot, the surfaces of said pins remote from said bearing surfaces being spaced from said bearing surfaces a distance substantially equal to the distance that the corresponding wall of the slot is spaced from said bearing surfaces for maintaining said bearing surfaces in slidable engagement with each other.
